UNITED STATES PATENT OFFICE

ARTHUR R. SLATER, OF SANTA CRUZ, CALIFORNIA

AIR-SUPPLY BUOY FOR SUBMARINES

Application filed July 25, 1928. Serial No. 295,167.

My invention relates to improvements in an air supply buoy detachably connected to the shell of a submarine and arranged to be released to carry a flexible air connection to the surface of the water to supply air to the submarine while submerged.

The primary object of my invention is to provide an improved device for supplying air to submarines in case the submarine is 10 unable to rise to the surface of the water before the air supply is exhausted.

Another object is to provide an improved device which is normally carried in sealing relation to a recess formed in the shell of a 15 submarine and which is displaceable from within the submarine for carrying an air connection to the surface of the water.

A further object is to provide an improved device in which a buoy is normally carried seated within a recess formed in the shell of a submarine and projecting only slightly from the surface thereof and which will effectually seal an air connection and mooring cable within such recess whereby the device 25 may be carried in an inoperative position without interfering with the normal operation of the submarine.

A further object is to provide an improved device provided with an air inlet connection 30 which is normally held tightly closed and which is automatically opened to admit a supply of air to a submerged submarine when an air supply buoy reaches the surface of the water.

Another object is to provide an improved device which is entirely operable from within the submarine whereby an air supply may be quickly and easily obtained in event of 35 accident while submerged.

A still further object is to provide an improved device of the character described which is simple in construction and which may be easily applied to a submarine and 40 kept ready for use in case of emergency.

I accomplish these and other objects by means of the improved device disclosed in the drawings forming a part of the present application wherein like characters of reference 45 are used to designate similar parts through-

out the specification and drawings and in which—

Fig. 1 is a vertical section of my improved air supply buoy as seated upon the shell of a submarine;

Fig. 2 is a bottom view of the device as shown in Fig. 1 and as seen from inside the submarine shell; and

Fig. 3 is a broken vertical section showing the buoy released and floating in operative 60 position.

Referring to the drawings, the numeral 1 is used to designate in general a buoy consisting preferably of a hollow floatable chamber having a tapered body portion 2 arranged to seat within the upper portion of a recess 3 formed in the shell 4 of a submarine and correspondingly tapered to form a seat for the body portion 2 of the buoy. The buoy is provided with an enlarged upper 70 portion forming a flange 6 arranged to seat upon the outer surface of the shell 4 around the recess, packing 7 being provided to insure a water-tight seat if desired.

An air inlet member designated in general 75 by the numeral 8 is mounted within the buoy 1, said member 8 having its upper portion extending outwardly through the closed top of the buoy and provided with a valve seat arranged to receive an outwardly opening 80 valve 9. A hood 11 is secured upon the top of the buoy 1 to extend over the outwardly extending end of the air inlet member and the valve, said hood having openings 12 formed adjacent the upper surface of the buoy to admit air as hereinafter more fully described. The member 8 is provided with an offset extension 13 extending downwardly through the bottom of the chamber. The valve 9 is provided with a stem 14 extending downwardly through an elongated guide 16 provided upon the bottom of the buoy, said stem 90 extending outwardly from the chamber through said guide. The guide 16 is arranged to form a water-tight connection around the 95 stem 14 in any suitable manner.

A tubular air connection 17 has one end extending into the body of the submarine through the bottom of the recess 3 as at 18, said connection opening into the submarine 100

and being secured thereto in any suitable manner. The other end of the air connection 17 is secured in connection with the inwardly extending end of the air inlet member 8. The tubular connection 17 is normally coiled within the lower portion of the recess 3 and is enclosed therein by the buoy 1 when seated in normal position in connection with the shell 4 of the submarine.

- 5 10 A mooring cable 19 has its ends secured to suitable shackles 21 and 22 secured upon the bottom of the buoy 1 and the bottom of the recess 3 respectively. The cable is normally coiled within the lower portion of the 15 recess 3 together with the tubular connection 17.

The buoy 1 is secured upon the shell 4 of the submarine in sealing relation to the recess 3 by means of suitable securing members 23 extending through the shell 4 into engagement with the flange portion 6 of the buoy. The members 23 preferably consist of bolts threaded into the flange portion of the buoy and operable from inside of the submarine for 25 clamping the buoy into tightly seated relation to the shell 4, and for releasing the buoy when desired. A plurality of displacing members 24 are threaded into the shell and arranged to be moved from inside of the submarine to 30 press the flange 6 outwardly away from the shell 4 when it is desired to release the buoy from the submarine.

A link 26 is pivotally mounted upon an arm 27 carried by the lower end of the guide 35 16 and slidably and pivotally connected to a pin 28 secured transversely through the lower end of the valve stem 14. The link 26 is arranged to be moved to lower the valve stem and hold the valve 9 firmly seated upon the 40 outer end of the air inlet member 8 when the buoy is seated upon the shell 4 as shown in Fig. 4 of the drawings. A spring 29 is mounted around the stem 14 and arranged to exert an outward pressure just sufficient to unseat 45 the valve 9 against atmospheric pressure.

In operation, the shell 4 is constructed to provide the recess 3 as shown and the tubular air connection 17 and the mooring cable 19 are secured between the bottom of the recess 50 3 and the hollow buoyant member 1 as shown, said connection 17 and cable 19 being coiled together within the lower portion of the recess 3 as shown in Fig. 1 of the drawings. The buoy 1 is seated within the recess 1 and 55 the securing members 23 are tightened from within the submarine to secure the buoy in seated position sealing the recess 3 and enclosing the air connection 17 and the cable 19. The link 26 is moved to tightly close 60 the valve 9 as the buoy is seated, thereby preventing water from entering the top of the air inlet member 8 when the submarine is submerged.

In the event the submarine is unable to 65 rise to the surface of the water after being

submerged, the securing members 23 are loosened to release the buoy, and if necessary the displacing members 24 are moved to unseat the buoy from the shell 4, thereby permitting the buoy to disengage the recess 3 and

rise to the surface of the water. As the buoy rises from the submarine, the tubular connection 17 and the cable 19 are uncoiled and their ends carried upwardly with the buoy. The link 26 releases the valve 9 as soon as the 75 buoy is released from the submarine. However, as the spring 29 is arranged to open the valve only against atmospheric pressure, the pressure of water against the upper surface of the valve 9 prevents said valve from 80 opening until the buoy reaches the surface.

As soon as the hydrostatic pressure is removed from the valve, the spring 29 raises the valve 9 and permits air to enter the top of the air inlet member 8 which is now supported by the 85 buoy above the surface of the water. Air may now be drawn into the submarine through the tubular member 17 to sustain life therein until the submarine may be raised to the surface. The hood 11 admits air to the 90 inlet 8 through the openings 12, but prevents any material amount of water splashing over the top of the buoy from entering the inlet 8. In event the valve stem 9 should stick and fail to be opened by the spring 29, air may 95 be pumped in any convenient manner to provide sufficient pressure within the tubular member 17 to open the valve after the buoy has floated to the surface of the water.

It will be noted that in normal position, 100 the buoy and its connection occupy but relatively little space and cause substantially no obstruction upon the surface or within the submarine, and no interference is caused to the ordinary operation of the submarine. 105 When released, the buoy is effectually moored to the submarine by the cable 19 so that a continuous supply of air may be drawn into the submarine through the connection 17.

While I have illustrated the principal of 110 my invention and one simple embodiment of the device, numerous modifications may of course be made without departing from the spirit of my invention. I therefore do not wish to restrict myself to the specific details 115 of construction as illustrated and described, but desire to avail myself of all modifications which may fall within the scope of the appended claims.

Having thus described my invention what 120 I claim as new and desire to secure by Letters Patent is—

1. An air supply buoy for submarines comprising a hollow floatable chamber having a body portion arranged to be received within a recess formed in the shell of a submarine; means operable from within the submarine for detachably securing the chamber in sealing relation to the recess; an air inlet member extending through the chamber; a flex- 125 130

ible tubular member having one end connected to the air inlet member and the other end connected to an opening into the submarine, said tubular member being normally coiled
 5 within the recess and enclosed therein by the chamber and being arranged to be extended to the surface of the water when the chamber is released; a valve mounted in connection with the outer end of the air inlet member
 10 and provided with a stem extending through the bottom of the chamber; means connected to said stem for normally holding the valve closed when the chamber is in normal position with the recess; and a spring mounted in
 15 connection with the stem for automatically opening the valve when the chamber rises to the surface of the water after being released from the submarine.

2. An air supply buoy for submarines comprising a hollow floatable chamber having a body portion arranged to be received within a recess formed in the shell of a submarine; means operable from within the submarine for detachably securing the chamber in sealing relation to the recess; an air inlet member extending through the chamber; a flexible tubular member having one end connected to the air inlet member and the other end connected to an opening into the submarine, said
 20 tubular member being normally coiled within the recess and enclosed therein by the chamber and being arranged to be extended to the surface of the water when the chamber is released; a valve mounted in connection with the outer end of the air inlet member and provided with a stem extending through the bottom of the chamber; means connected to said stem for normally holding the valve closed when the chamber is in normal position
 25 with the recess; a spring mounted in connection with the stem for automatically opening the valve when the chamber rises to the surface of the water after being released from the submarine; and a mooring cable connect-
 30 ed between the chamber and the submarine and normally coiled within the recess with the tubular member to moor the chamber to the submarine when released.

3. An air supply buoy for submarines comprising a hollow floatable chamber having a tapered body portion arranged to seat with a correspondingly tapered portion of a recess formed in the shell of a submarine; means operable from within the submarine
 35 for detachably securing the chamber in sealing relation to the recess; an air inlet member extending through the chamber; a flexible tubular member having one end connected to the inlet member and the other end connected to and opening into the body of the submarine, said tubular member being normally enclosed within the recess by the chamber and arranged to be extended to the surface of the water when the chamber is released from the submarine; a

valve mounted in connection with the outer end of the air inlet member and provided with a stem extending through the bottom of the chamber; means mounted in connection with said stem for holding the valve in closed position when the chamber is in normal position within the recess; and a spring mounted in connection with the stem for automatically opening the valve when the chamber rises to the surface of the water after being released from the submarine. 70
 75

4. An air supply buoy for submarines comprising a hollow floatable chamber having a tapered body portion arranged to seat within a correspondingly tapered portion of a recess formed in the shell of a submarine and also having a flange arranged to seat against the surface of the submarine around the recess; means extending through the shell into engagement with the flange for detachably securing the chamber in seated position sealing the recess; means extending through the shell and operable from within the submarine for displacing the chamber outwardly from the recess; an air inlet member extending through the chamber; a flexible tubular member having one end connected to the air inlet member and the other end connected to and opening into the submarine; a valve mounted in connection with the outer end of the air inlet member and provided with a stem extending through the chamber; means connected to the stem for normally closing the valve when the chamber is seated within the recess; and a spring arranged to automatically open the valve when the chamber rises to the surface of the water after being released from the submarine. 80
